UNITED STATES PATENT OFFICE.

EDWARD E. WORKMAN, OF LYONS, INDIANA, ASSIGNOR OF ONE-HALF TO ELIAS MEES,
OF LYONS, INDIANA.

MOLD FOR PLASTIC BLOCKS.

1,092,195.

Specification of Letters Patent.

Patented Apr. 7, 1914.

Application filed August 30, 1912. Serial No. 717,978.

To all whom it may concern:

Be it known that I, EDWARD E. WORKMAN, a citizen of the United States, residing at Lyons, in the county of Greene and State of 5 Indiana, have invented a new and useful Mold for Plastic Blocks, of which the following is a specification.

The present invention relates to a mold for plastic blocks, such as are employed in 10 constructing silos, bridges, culverts, water tanks and reservoirs and the like.

It is the primary object of the present invention to provide a mold for such blocks, which may conveniently form a lock tongue 15 and groove at the sides of the block in order that adjacent blocks may be interlocked.

This invention also contemplates the provision of a mold of the character indicated which may be utilized for molding various 20 sizes and styles of blocks, the mold being simple and inexpensive in construction, as well as convenient, efficient, and serviceable in its use.

To the above ends, the present invention 25 resides in the novel construction, arrangement and combination of parts hereinafter set forth and claimed, it being understood that the details are capable of alterations or deviations within the scope of the appended 30 claim without departing from the spirit of the invention or sacrificing any of the benefits derived.

The invention has been illustrated in its preferred embodiment in the accompanying 35 drawings, wherein like reference characters have been employed to denote corresponding parts, and wherein—

Figure 1 is a perspective view of the mold, the several parts being in separated positions. Fig. 2 is a longitudinal section of the mold. Fig. 3 is a transverse section thereof. Fig. 4 is a view similar to Fig. 3, illustrating another use of the mold. Fig. 5 is a sectional detail illustrating a modification. 45 Fig. 6 is a view similar to Fig. 5 illustrating another modification. Fig. 7 is a sectional detail illustrating another use of the mold. Fig. 8 is a sectional detail taken on a plane at right angles to the plane of section of Fig. 50 7. Fig. 9 is a perspective view of a detail.

Referring specifically to the drawings, the numeral 10 designates a suitable bed plate, which is provided at each end with two series of sockets or apertures 11 and which 55 is provided at each side with two series of

sockets or apertures 12, the respective series of sockets 11 and 12 being arranged longitudinally and transversely respectively.

A pair of side pieces are arranged on the bed plate 10, one of the pieces being designated by the numeral 13 and the other piece comprising two complementing parts or sections 14. Each of the parts 14 has a concaved channel 15 along its inner edge, the two channels 15 coöperating so as to provide a groove between the parts 14. The groove provided by the channels 15 is approximately circular, and a pair of short cylindrical blocks 16 are slidable in the ends of the said groove, the outer faces of the blocks 16 being flattened so as to be flush with the inner edges of the parts 14.

End pieces 17 and 18 are arranged on the bed plate 10 between the ends of the side pieces, said end pieces being provided with 75 the respective tongue 19 and groove 20 for forming a groove and a tongue at the respective ends of the block. The end piece 18 is provided at its end adjacent the side piece 13 with a groove 22 through which a rod or 80 stick 21 passes, the said rod being circular in cross section with its outer side flattened to lie against the inner edge of the side piece 13.

The end pieces 17 and 18 are slidable between the side pieces so that the end pieces may be adjusted for forming various lengths of blocks, the rod 21 being adjusted to abut against the end piece 17. The rod 21 co-operates with the side piece 13 so as to form a lock groove along one side of the block, whereas the groove in the other side piece forms a lock tongue along the other side of the block, the block 16 being adjustable to correspond with the end pieces. 85

The end and side pieces are retained in position by means of pins or stops 23 engaged in the corresponding sockets 11 and 12, as will be apparent, the said pins preventing the said pieces from moving outwardly or away from each other. Thus, when the end and side pieces have been set together on the bed plate 10 and the rod 21 and blocks 16 have been properly adjusted, concrete or other plastic material may be 100 poured or placed between the said pieces, and may be leveled in the usual fashion. The block thus formed when dry or hardened, may be removed by withdrawing the pins 23, in which event, the two end pieces 105 110

and the side piece 13 are readily removable. The two parts 14 of the other side piece being separable permit the lock tongue along one side of the block to be removed, and the 5 rod 21 may be withdrawn endwise from the lock groove formed along the other side of the block. The block thus formed is provided at its sides with a lock tongue and a lock groove respectively, in order that adjacent blocks may be locked together by an 10 endwise movement, as will be apparent and as is common practice. The block is thus formed in a convenient and simple manner.

15 It is understood, that the inner edges of the side pieces may be beveled so as to bevel the sides of the block when the block is to be employed for constructing silos and other cylindrical structures, and the end pieces may be of various lengths, in order to give
20 the block the proper width when molded. One end piece may be slightly larger than the other so as to give the block a slight taper, if preferred, when the silo or other structure is to taper, and various other
25 changes may be made in the details within the scope of the appended claim without departing from the spirit of the invention, in order that the blocks molded may suit the circumstances. The tongue and groove at
30 the ends of the block also permit the ends of adjoining blocks to engage each other as is obvious.

As illustrated in Fig. 4, the block or slab is provided with a passage or doorway by means of a frame 24 placed on the center of the bed plate around which the plastic material is molded, the said frame having a flange 25 in order to provide a rabbet around the doorway. This frame or core 24 may be of any suitable pattern, and other cores may be employed for providing bolt holes for securing a door frame in position, as is well understood in molding.

As illustrated in Fig. 5, the end piece 18^a is provided with a modified form of groove 20^a for providing a beveled tongue at the end of the block, whereas in Fig. 6, the end piece 18^b is provided with a V-shaped groove

20^b for providing a V-tongue at the end of the block. It is manifest, therefore, that the 50 details may be altered according to the uses to which the blocks are to be put, such as for constructing silos, bridges, culverts, water tanks and reservoirs and the like.

As shown in Fig. 7, a vertical piece 26 55 may be set on the side pieces of the mold, said piece having a dropped or depending portion 27 fitting within the side pieces of the mold, so as to provide a groove in the face of the block. One or more of the pieces 60 26 may be employed for providing a groove or grooves in the face of the block for any particular purpose.

From the foregoing taken in connection with the drawings, the advantages and capabilities of the present device will be apparent, and it will also appear, that the objects aimed at have been carried out in a satisfactory manner. 65

Having thus described the invention, what 70
is claimed as new is:—

A mold for plastic blocks embodying a bed plate, side pieces thereon, one of the side pieces having an inner lock tongue forming groove of circular cross section, end pieces 75 slideable between the side pieces, and having an inner tongue and groove, respectively, one end piece having a groove in its end adjacent the other side piece, a lock groove-forming rod of circular cross section slideable through the groove last mentioned in the end piece and having one side flattened and resting against the latter side piece, blocks slideable in the groove of the former side piece to coöperate with the respective 80 ends of the end piece, and adjustable means 85 for retaining all of said pieces against separation on the bed plate.

In testimony that I claim the foregoing as my own, I have hereto affixed my signature in the presence of two witnesses. 90

EDWARD E. WORKMAN.
